UNITED STATES PATENT OFFICE

156,543

ICE-CREAM SCOOP

Bert F. Lawrence and Emma Ethel Lawrence,
Portland, Oreg.

Application October 23, 1948, Serial No. 149,264

Term of patent 14 years

(Cl. D44—29)

To all whom it may concern:

Be it known that we, Bert F. Lawrence and Emma Ethel Lawrence, citizens of the United States, residing at Portland, in the county of Multnomah and State of Oregon, have invented a new, original, and ornamental Design for Ice-Cream Scoops, of which the following is a specification, reference being had to the accompanying drawing, forming part thereof.

We claim:

The ornamental design for an ice-cream scoop, as shown.

BERT F. LAWRENCE.
EMMA ETHEL LAWRENCE.
